UNITED STATES PATENT OFFICE.

ROBERT R. DEBACHER, OF NEW YORK, N. Y.

DESIGN FOR A HANDLE FOR TOILET ARTICLES.

SPECIFICATION forming part of Design No. 36,022, dated August 26, 1902.

Application filed May 9, 1902. Serial No. 106,650. Term of patent 14 years.

To all whom it may concern:

Be it known that I, ROBERT R. DEBACHER, a citizen of the United States, and a resident of the borough of Manhattan, in the city and State of New York, have invented a new, original, and ornamental Design for a Handle for Toilet Articles, of which the following is a specification, reference being had to the accompanying drawings, forming part thereof.

Figure 1 is a plan view of the handle, showing my new design. Fig. 2 is a side view of the same, and Fig. 3 is an end view of the handle.

As shown in the drawings, the leading or material feature of my design consists in a handle for toilet articles having a smooth cylindrical portion 1 at one end, a smooth tapered portion 2 at the other end, and an intermediate portion 3, presenting an irregular

outline when viewed from any direction, the 20 end of the irregular portion 3 adjacent to the tapered portion 2 being spread out irregularly, as shown at 4, the said intermediate portion 3 presenting a vertical stripe 5 when viewed in side elevation. 25

What I claim is—

The ornamental design for a handle for toilet articles, substantially as herein shown and described.

In testimony that I claim the foregoing as 30 my invention I have signed my name, in presence of two witnesses, this 5th day of May, 1902.

ROBERT R. DEBACHER.
